UNITED STATES PATENT OFFICE

2,120,411

DISPLAY DEVICE

Albert Koeble, Irvington, N. J., assignor to American Lithographic Division of the United States Printing and Lithograph Company, a corporation of Ohio

Application March 23, 1937, Serial No. 132,475

7 Claims. (Cl. 211—135)

This invention relates to display devices and particularly to that class thereof formed from sheet material, such as cardboard, adapted to be erected in upright position and provided with 5 transverse shelves for the reception of merchandise to be displayed.

With these ends in view, and others which will be pointed out more in detail herein, my improvements comprise features illustrated in the 10 drawings accompanying this specification, wherein:

Figure 1 is a front elevation of my improved device in erected condition.

Fig. 2 is a plan view of what is shown in Fig. 1. 15 Fig. 3 is an upright end view looking in the direction of arrow 3 of Fig. 2.

Fig. 4 is a central vertical section on line 4—4 of Fig. 1.

Fig. 5 is a vertical section on line 5—5 of Fig. 1. 20 Fig. 6 is a fragmentary cross section on line 6—6 of Fig. 1.

Fig. 7 is a rear elevation showing one step in folding the device for packing and shipping.

Fig. 8 is a view similar to that of Fig. 7 showing 25 a further step in folding the device.

Fig. 9 is a front elevation of the principal blank of the device in extended position.

Fig. 10 is a plan view of one of the shelves in 30 extended position.

Fig. 11 is a plan view of the back member.

Figs. 1 to 6 inclusive are to one scale and Figs. 7 to 11 inclusive are to one scale, about two-thirds of that of the earlier figures.

Main member 2, Fig. 9, comprises a mid-panel 3, to the right vertical edge of which is articulated at 4, side panel 5 and to the left vertical edge at 6, side panel 7. To the outer edge of panel 5 is articulated at 8, end panel 9, and to the outer edge of panel 7 is articulated at 10, end panel 11. These five panels are preferably formed from one piece of sheet material and are provided with openings therethrough respectively, the forms and functions of which will appear later herein. It will be noted that mid-panel 3 has its lower edge 12 slightly longer than similar edges of the other panels, so that when the device is erected, the whole will be tipped back slightly to throw the center of gravity well within the device, thereby adding to its stability.

One or more shelves, two are shown in Fig. 1, are provided. As these shelves are alike, a description of the upper one will suffice for both. Referring particularly to Fig. 10 shelf 32 comprises mid-panel 13, opposite end panels 14, 15 articulated thereto at 16, 17 respectively, and a front edge strip 18 articulated at 38 to the front or lower edges of the said three panels. Said end panels have their front edges curved at 28, 29 respectively and said strip 18 extends trans-

versely in either direction beyond said end panels and is adapted to have its ends bent around under the opposite curved ends 28, 29 of end panels 14, 15, and said strip 18 is provided with opposite hooks 19, 20 for engagement with slots 5 33, 31 in end panels 9 and 11 of main member 2, thus providing supports for said shelf end panels, all respectively, Figs. 10, 9, 3 and 6.

Panels 14, 15 have articulated to their upper or rear edges, ears 21, 22 adapted to be bent down for engagement with ears 23, 24, cut out from end panels 9 and 11 respectively. Mid-panel 13 of said shelf is provided with flange 25, articulated to its rear edge, and said flange is fixed to the upper end of back member 26 by 15 some convenient means, as an adhesive, see Fig. 4. Said shelf is thereby hinged at 27 to back member 26.

The upper portion of mid-panel 3 of main member 2 may carry printed thereon suitable 20 legends describing the goods displayed and the lower portion is preferably provided with an opening 33, through which may be seen any merchandise displayed on the central panel of the lower shelf, see Figs. 1, 4 and 9. Panels 5 and 7 25 of main member 2 are provided with openings 34, 35 respectively for the reception and support of shelf 32. Referring particularly to opening 35, lower ledge 37 thereof is adapted to support panel 15 of shelf 32, which rests thereon 30 and downwardly extending slot 36 is engaged by strip 18 of said shelf.

In assembling the device, side panels 5 and 7 of main member 2 are folded backwardly at right angles to mid-panel 3, and end panels 9 and 11 are folded outwardly at right angles to panels 5 and 7, all respectively, see Fig. 2. The flanges of the shelves are fixed to back member 26, see Fig. 4, as to flange 25 of shelf 32, and ears 21, 22 are hooked into engagement with ears 23, 24 40 of end panels 9, 11 of main member 2, respectively.

An essential feature of my improved display device resides in its ability to be collapsed into flat form for packing and shipping. The steps in folding the device are as follows; first, hooks as 19, 20 of strip 18 are unhooked from their respective slots, as 30, 31, in end panels 9 and 11. Then back member 26 is moved vertically upward, causing the shelf ears, as 21, 22, to release 50 their engagement with ears 23, 24 of end panels 9, 11, all respectively, and said shelves swing upwardly and forwardly about front edge 38 as a fulcrum in the openings, as 34, 35 of panels 5 and 7, and finally fold flat against mid-panel 3 55 of main member 2. Then panels 7 and 11 are folded over onto back member 26, and opposite panels 5 and 9 are folded against panels 7 and 11, Fig. 8. That leaves the shelf end panels, as 15 of shelf 32, free to be folded to the left, Fig. 7, 60

down onto panel 9 of main member 2, Fig. 8. After said folding, opposite shelf panels, as 14 of shelf 32, may be folded to the right, Fig. 8, onto panels 5 and 9 of main member 2, thereby forming a compact assembly for shipping.

5 I claim:

1. A display device including in combination a main member comprising a mid-panel, opposite side panels articulated to said main panel, opposite side end panels articulated to said side panels, said side panels extending backwardly from said mid-panel and said end panels extending outwardly from said side panels, all respectively, a shelf having a mid-panel with a flange articulated to its rear edge, openings through the side panels of said main member for the reception of said shelf, ledges at the lower edges of said openings for the support of said shelf respectively, and a back member, said shelf mid-panel flange being articulated to said back member.

10 2. A display device including in combination a main member comprising a mid-panel, opposite side panels articulated to said main panel, opposite end panels articulated to said side panels, said side panels extending backwardly from said mid-panel and said end panels extending outwardly from said side panels, all respectively, a shelf comprising a mid-panel and two opposite end panels articulated thereto, said panels being provided with ears articulated to their rear edges respectively, a front edge strip articulated to the mid-panel and end panels of said shelf and having hooks at either end thereof, openings through the side panels of said main member for the reception of said shelf, ledges at the lower edges of said openings for the support of said shelf, ears cut from said main member end panels for engagement with said shelf ears, slots in the main member end panels for engagement with said shelf front edge strip hooks, all respectively, and a back member, the mid-panel of said shelf being articulated to said back member.

15 3. A display device including in combination a main member comprising a mid-panel, opposite side panels articulated to said main panel, opposite end panels articulated to said side panels, said side panels extending backwardly from said mid-panel and said end panels extending outwardly from said side panels, all respectively, a plurality of shelves, each comprising a mid-panel and two opposite end panels articulated thereto, said end panels being provided with ears articulated to their rear edges respectively, openings through the side panels of said main member for the reception of said shelves, ledges at the lower edges of said openings for the support of said shelves respectively, an opening through the main member mid-panel below the upper shelf, and a back member, the mid-panels of said shelves being articulated to said back member.

20 4. A display device including in combination a main member comprising a mid-panel, opposite side panels articulated to said main panel, opposite side end panels articulated to said side panels, said side panels extending backwardly from said mid-panel and said end panels extending outwardly from said side panels, all respectively, a plurality of shelves, each comprising a mid-panel and two opposite end panels articulated thereto, said end panels being provided with ears articulated to their rear edges respectively, a front edge strip articulated to each of said mid-panels and end panels and having hooks at either end thereof, openings through the side panels of

said main member for the reception of said shelves, ledges at the lower edges of said openings for the support of said shelves, all respectively, ears cut from said main member end panels for engagement with said ears, slots in the main member end panels for engagement with said shelf front edge strip hooks all respectively and a back member, the mid-panels of said shelves being articulated to said back member.

25 5. A collapsible display device including in combination a main member comprising a mid-panel, opposite side panels articulated to said main panel, opposite end panels articulated to said side panels, said side panels extending backwardly from said mid-panel and said end panels extending outwardly from said side panels all respectively, a plurality of shelves, each comprising a mid-panel and two opposite end panels articulated thereto, openings through the side panels of said main member for the reception of said shelves, ledges at the lower edges of said openings for the support of said shelves respectively and a back member, said shelf mid-panel flange being articulated to said back member, whereby when said back member is pushed upwardly, said shelves are caused to swing upwardly and forwardly on their front edges as fulcrums and fold against the mid-panel of the main member.

30 6. A collapsible display device including in combination a main member comprising a mid-panel, opposite side panels articulated to said main panel, opposite end panels articulated to said side panels, said side panels extending backwardly from said mid-panel and said end panels extending outwardly from said side panels all respectively, a shelf comprising a mid-panel and two opposite end panels articulated thereto, openings through the side panels of said main member for the reception of said shelf, ledges at the lower edges of said openings for the support of said shelf respectively, and a back member, said shelf mid-panel flange being articulated to said back member, whereby when said back member is pushed upwardly, said shelves are caused to swing upwardly and forwardly on their front edges as fulcrums and fold against the mid-panel of the main member, said side and end panels of said main member being then free to be folded backwardly onto said back member, and said shelf end panels being thereafter free to be folded onto said main member side and end panels, thus forming a compact assembly of the device.

35 7. A collapsible display device including in combination a main member comprising a mid-panel, opposite side panels articulated to said main panel, opposite end panels articulated to said side panels, said side panels extending backwardly from said mid-panel and said end panels extending outwardly from said side panels, all respectively, a plurality of shelves, each comprising a mid-panel and two opposite end panels articulated thereto, said end panels being provided with ears articulated to their rear edges, openings through the side panels of said main member for the reception of said shelves, ledges at the lower edges of said openings for the support of said shelves all respectively, an opening through the main member mid-panel below the upper shelf and a back member, the mid-panels of said shelves being articulated to said back member.

ALBERT KOEBLE.
